UNITED STATES PATENT OFFICE.

CARSTEN TRUELSEN, OF LOUP, NEBRASKA.

CHURN AND EGG-BEATER.

SPECIFICATION forming part of Letters Patent No. 741,946, dated October 20, 1903.

Application filed June 28, 1901. Serial No. 66,413. (No model.)

To all whom it may concern:

Be it known that I, CARSTEN TRUELSEN, residing at Loup city, in the county of Sherman and State of Nebraska, have invented certain useful Improvements in Churns and Egg-Beaters; and I do hereby declare that the following is a full, clear, and exact description of the invention, such as will enable others skilled in the art to which it appertains to make and use the same, reference being had to the accompanying drawings, which form a part of this specification.

This invention has relation to a new and novel improvement in a combination churn and egg-beater.

The object of my invention is to provide a churn mechanism adapted to be secured to any suitable crock, jar, or pail and embodies certain adjustable features, described more fully hereinafter.

In the accompanying drawings I have shown in Figure 1 a side elevation, with portions broken away, of a combination churn and egg-beater embodying my invention, while Fig. 2 shows a top view of my improvement as secured to an ordinary crock.

In carrying out the aim of my invention, which is to provide a dasher mechanism adapted to be adjustably and detachably secured to a suitable vessel, I construct a supporting-plate 2, which is provided with suitable slots *x* and has an upward extension 3, as is shown in the drawings. This upward extension 3 is provided with a central slot 4 and a rack-face 5, as will be noticed in referring to Fig. 1. Pivoted secured by means of two bolts 27, which work through the slots *x* and held by means of the nuts *k*, are the striding keepers 26, through which pass the screws 30, so that by means of these keepers the mechanism is secured to a suitable crock A, as is shown in Fig. 1, for instance. These keepers 26 working through the slots *x* permit the mechanism to be adjusted to a crock of any suitable size.

Secured adjustably to the upward rack or notch-faced extension 3 is a horizontally-disposed bar 8, provided with the bearing *b*, which bearing *b* revolvably supports a driving-shaft 13, as shown. The bar 8 is provided with the slot *a* and is also provided with a ridge adapted to register with the notches within the bar

3, so that this bar 8, provided with the bearing *b*, can be raised upward or downward and shovved inward or outward, being held by means of a bolt 6, working upon a suitable washer 7, as is clearly shown. This bar 8 is provided with a laterally-extending flange 9 upon one side, to which flange is secured the substantially U-shaped frame 12, this frame being secured by means of the rivets 10, as shown.

Secured to the driving-shaft 13, which passes through the bearing *b*, is a gear-wheel 14, which meshes with the pinions 15 and 16, as shown. The gear-wheel 14 is provided with a hub *e* and by means of a pin *c* is secured to the shaft 13. Upon the opposite end the shaft 13 is provided with an operating-handle *g*, held by means of the screw *f* and provided with the handle *h*, so that this gear 14 may be revolved.

Working within the lower end of the frame 12, which provides a bearing, is a tube 17, which is slidably held within the lower portion of this frame 12, and mounted upon this tube 17 is a gear-wheel 15, adjustably secured thereto by means of the screw *i*, so that this tube 17 is kept from sliding outward by means of this screw *i*, which passes through the hub *e* of the pinion 15. Extending longitudinally through this tube 17 and revolvably held therein is the shaft 23, which above passes through the upper end of the frame 12 and through the upper pinion 16, which pinion 16 is adjustably secured to the dasher-shaft 23 by means of the screw *j*. This dasher-shaft 23 is made to project a suitable distance beyond the frame 12, so that this shaft 23 may be slid upward or downward relative to the frame 12, as may also the sliding tube 17, to which tube below is secured the dasher-frame 20 by means of the screw 18, this dasher-frame below being provided with a hub 21, through which the dasher-shaft 23 extends, which is provided with an adjustable dasher 25, held by means of the screw 24. By this arrangement this device may be used either as an egg-beater in a shallow dish in carrying both the sliding sleeve and dasher-shaft upward and carrying the bearing upward or be used as a dasher in a deep vessel in bringing the bearing *b* downward and carrying and extending the shaft and sliding tube outward.

The invention is noticeable because of its simplicity, and,

Having thus described my said invention, what I claim as new, and desire to secure by 5 United States Letters Patent, is—

1. In a device of the class described, the combination with a supporting-plate having means for detachably connecting the same to a receptacle and provided with a vertically-disposed slotted extension one face of which is notched or serrated, of a horizontally-disposed bar associated with said extension and extending across the same, said bar having a longitudinal slot therein, a bolt arranged in 10 the slots of said extension and bar for clamping the bar in engagement with the notched or serrated face of the extension and permitting adjustment of the bar vertically and laterally with respect to said extension, a vertically-disposed flange carried by said bar, a supporting-frame connected to said flange, dasher mechanism carried by said frame, and means carried by said bar for operating said dasher mechanism.
2. In a device of the class described, the combination with a supporting-plate having means for detachably connecting the same to a receptacle and provided with a vertically-disposed slotted extension one face of which is notched or serrated, of a horizontally-disposed bar associated with said extension and extending across the same, said bar having a longitudinal slot therein and also provided with a bearing, a bolt arranged in the slots of 25 said extension and bar for clamping the bar in engagement with the notched or serrated

face of the extension and permitting adjustment of the bar vertically and laterally with respect to said extension, a vertically-disposed flange carried by said bar, a supporting-frame 40 connected to said flange, dasher mechanism carried by said frame, a shaft journaled in the bearing of said horizontal bar and geared to the dasher mechanism, and means for operating said shaft.

3. In a device of the class described, the combination with a supporting-plate having means for detachably connecting the same to a receptacle and provided with a vertically-disposed slotted extension one face of which is notched or serrated, of a horizontally-disposed bar associated with said extension and extending across the same, said bar having a longitudinal slot therein and also provided with a bearing, a bolt arranged in the slots of 50 said extension and bar for clamping the bar in engagement with the notched or serrated face of the extension and permitting adjustment of the bar vertically and laterally with respect to said extension, a vertically-disposed flange carried by said bar, a supporting-frame 55 connected to said flange, dasher mechanism carried by said frame and adjustable relatively thereto, a shaft journaled in the bearing of said horizontal bar and geared to the dasher mechanism, and means for operating said shaft.

CARSTEN TRUELSEN.
